United States Patent Office Notice of Allowance for U.S. Appl. No. 29/514,536 dated Apr. 28, 2015 (6 pages).

Primary Examiner — Robert M. Spear*Assistant Examiner* — Kendra L Hamilton(74) *Attorney, Agent, or Firm* — Michael Best & Friedrich LLP(57) **CLAIM**

What is claimed is the ornamental design for a wireless transmitter, as shown and described.

DESCRIPTION

FIG. 1 is a bottom right perspective view of the wireless transmitter;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the Figures shown in broken lines disclose environmental structure and form no part of the claimed design.
